UNITED STATES PATENT OFFICE.

AUGUST SEELING, OF SHERODSVILLE, OHIO.

SKIRT-MARKER.

985,070.

Specification of Letters Patent. Patented Feb. 21, 1911.

Application filed April 20, 1910. Serial No. 556,572.

To all whom it may concern:

Be it known that I, AUGUST SEELING, a citizen of the United States of America, residing at Sherodsville, in the county of Carroll and State of Ohio, have invented certain new and useful Improvements in Skirt-Markers, of which the following is a specification, reference being had therein to the accompanying drawing.

10 This invention relates to skirt gages and markers, and the principal object of the same is to provide a gage and marker that may be detachably fastened to the edge of a table, stand, bench, step or the like so that 15 a skirt may be accurately marked, said gage and marker being provided with a novel marker supporting arm which is formed of flexible material and which is pivotally connected to the device, thereby providing an 20 arm that may be rocked to various positions and materially facilitates the marking of a skirt.

In carrying out the objects of the invention generally stated above it will be understood, of course, that the essential features thereof are necessarily susceptible of changes in details and structural arrangements, one preferred and practical embodiment of which is shown in the accompanying 30 drawings, wherein:—

Figure 1 is a perspective view of the improved skirt gage and marker. Fig. 2 is a detail perspective view showing the practical application of the gage and marker. 35 Fig. 3 is a transverse sectional view showing the chalk carrier and its supporting arm.

Referring to the accompanying drawings by numerals, it will be seen that the improved skirt gage and marker comprises a clamp the body 1 of which is provided with relatively spaced laterally projecting jaws 2—3, one of which is provided with an adjustable clamping screw 4 by means of which the clamp may be fastened to an 40 overhanging edge of a stand 5, as shown in Fig. 2. Said body 1 is cut away on one longitudinal surface to provide a seat 5^a for one end of a vertical standard 6. Said standard is riveted or otherwise rigidly fastened to said body. The angular base 7 of 45 body 1 has its free end bifurcated to provide pivot ears 8 between which one end of a marker supporting arm 9 is pivoted. Said arm is flat and formed of thin flexible material, and adjacent its connection with ears 8, 50 is twisted, as indicated at 10 so that the

major portion of said arm will present a flat surface to standard 6. Said arm is provided with graduations designating inches and fractions thereof.

A chalk holder is adjustably mounted on arm 9, said holder comprising a body 11 which is provided with a central slot 12 through which arm 9 passes, and with a threaded transverse opening 13 which intersects slot 12 and in which a set screw 14 is mounted for locking said body to said arm. At its inner end, said body is reduced and provided with a reentrant slot 15 that extends the entire width of said body, and in which the chalk holding arms 16 are mounted. Said arms are preferably formed of a single length of thin resilient material bent to provide said arms 16 which are arranged in spaced parallel relation and 65 the connecting portion 17 which is of the same length as slot 15 and into which said connecting portion is fitted.

In use, the improved marker and gage is clamped to the edge of a table or stand, 80 and the skirt placed over standard 6. The chalk holder is adjusted to the desired point on arm 9, and the skirt slowly turned while the chalk holder is in contact therewith, thereby marking the skirt. It will be seen, 85 that the standard 6 being on the inside of the skirt provides a firm backing so that a clear and distinct mark may be placed on the outer surface of the skirt, and also that the hinged connection between arm 9 and 90 the base of the clamp, together with the flexibility of the arm 9, which is materially increased by its twisted portion 10, provides means whereby various movements of said arm relative to said standard may be had. 95

What I claim as my invention is:—

1. A skirt gage and marker comprising a standard, a clamp for detachably connecting the same to a support, said clamp provided with pivot ears, a flat flexible arm pivotally connected to said ears, said arm provided with a twisted portion so that it will present a flat surface to said standard, and marking means adjustably carried by said arm.

2. A skirt gage and marker comprising a clamp, said clamp provided with a standard seat and with laterally projecting pivot ears at the base, a standard having one end fastened to said seat, a flexible arm pivotally connected to the ears of said clamp, and 105 marking means adjustably carried by said arm.

3. A skirt gage and marker comprising a clamp having an angular base, said base provided with pivot ears, said clamp also provided with a standard seat, a standard fastened to said seat, a flexible arm pivotally connected to said ears, said arm provided with a twisted portion so that a flat surface is presented to said standard, and a chalk holder adjustably carried by said arm.
- 10 4. A skirt gage and marker comprising a clamp, a standard carried by one end thereof, a supporting arm hinged to the other

end thereof, a marker body having a central slot for adjustable engagement with said arm, means for locking said body to said arm, said body provided with a reentrant slot at one end, and chalk holding arms fitted in said reentrant slot. 15

In testimony whereof I hereunto affix my signature in presence of two witnesses.

AUGUST SEELING.
